UNITED STATES PATENT OFFICE.

FRED NELSON CRIPPEN, OF PASADENA, CALIFORNIA.

TUBING BLEEDER.

Application filed June 12, 1922. Serial No. 567,557.

To all whom it may concern:

Be it known that I, FRED NELSON CRIPPEN, a citizen of the United States, residing at Pasadena, in the county of Los Angeles and State of California, have invented a new and useful Tubing Bleeder, of which the following is a specification.

This invention relates to tubing-bleeders and is particularly directed to an improvement over the type of device illustrated and described in Patent No. 1,150,661 issued August 17, 1915, to G. C. Bushong.

The object of the present invention is to provide a tubing-bleeder which may be attached to the standard right-hand threaded well tubing and in which the requirement of a special length of left-hand threaded tubing, as well as the provision of special lugs or collars attached to said tubing length is eliminated.

Another object is to obtain maximum simplicity in a tubing-bleeder of the above character.

Various other objects and advantages will be more fully apparent from the following description of the accompanying drawings, which form a part of this disclosure, and which illustrate a preferred form of embodiment of the invention.

30 Of the drawings—

Figure 1 is a vertical section of an oil well provided with the improved tubing bleeder.

Fig. 2 is an enlarged sectional detail of a portion of Fig. 1 showing the parts in normal position.

Fig. 3 is a similar view showing the parts in operated position.

Fig. 4 is a perspective view of the barrel.

Fig. 5 is a perspective view of the releasable collar which is associated with the well tubing.

Fig. 6 is a perspective view of the stationary collar which is associated with the barrel.

The present embodiment of the invention is shown in connection with a well casing 1, in which is arranged a line of pump tubing comprising a plurality of length 3 of standard right-hand threaded tubing joined together by couplings 4 in the usual manner. The bleeder is positioned between the two adjacent sections or lengths 3, and a pump barrel 5 is connected to the lowermost section at the lower end thereof. The pump piston or plunger 6 is connected to a pump

or sucker rod 7 leading to the pumping mechanism at the surface.

In pumps of this character, sand is very liable to gain access to the pump tubing, 60 heaping up on top of the plunger, as indicated at 8, and causing further operation of the pump exceeding difficult or impossible.

It then becomes necessary to pull the pump tubing from the well and with it the 65 entire volume of oil above the sand. The weight of the oil column renders this pulling operation exceeding difficult and by pulling the filled tubing the oil therein is 70 wasted.

By providing a tubing-bleeder of the character herein referred to, the oil column may be released from the tubing prior to such pulling operation.

The tubing-bleeder illustrated in the 75 drawings comprises a stationary collar 10 having a right-hand internal screw-thread at its lower end by which it is screwed upon the upper threaded end of a tubing section 3. A perforated barrel 11 has an internal 80 right-hand screw-thread at its lower end and is screwed upon the upper end of the collar 10, the upper end of the barrel having an inwardly projecting flange 12. The upper end of the bore of the collar 10 has a 85 left-hand internal screw-thread which adapts it for engagement by the lower left-hand screw-threaded end of a releasable collar 13 positioned within the barrel 11. The upper end of the bore of the collar 13 has a 90 right-hand screw-thread adapting it to be screwed upon the lower right-hand screw-threaded end of the adjacent section 3 of pump tubing.

With this construction I have eliminated 95 the necessity of providing a special left-hand threaded section of tubing and as the collar 13 serves as an abutment to limit the relative releasing movement of the parts, the tubing need not have any projections or 100 collars attached thereto as in the above mentioned patented structure.

A valve sleeve 15 is arranged on the lowermost tubing section, and a sleeve valve seat 16 is arranged within the well casing 1. 105 When the well tubing is lowered from the position shown in Fig. 1, to that shown in Figs. 2 and 3, the sleeve 15 will engage the seat 16 and seal the interior of the casing 1 between said casing and the well tubing. 110

The operation of the improved tubing-bleeder is as follows: When sand has col-

lected in the well tubing as indicated at 8, and it is desired to bleed the tubing to release its column of oil, the tubing is lowered until the sleeve valve 15 engages the 5 casing seat 16 and seals the well casing as above described.

The tubing is then engaged at the well surface and turned in a right-hand direction causing the lower left-hand screw-threaded end of the collar 13 to be unscrewed from the stationary collar 10. After the collar 13 is fully disengaged from the collar 11 the tubing is elevated as shown in Fig. 3, and the oil within the tubing above 10 the sand will drain out through the perforations of the barrel 11 and into the well casing. The collar 13 by its engagement with the flange 12 of the barrel 11 limits the separating movement of the tubing sections and prevents their complete disengagement.

After the oil has run out of the tubing the tubing may be easily pulled and cleaned of sand, or the collar 13 may be reengaged 25 with the collar 10 without pulling the tubing, if desired.

With a tubing-bleeder of the above character, it is not necessary to provide a special length of left-hand threaded tubing or 30 to shrink a collar on such tubing. This is of great importance for the reason that if such special length of tubing is required it then becomes a part of the bleeder and has to be shipped to the field of use, whereas 35 with a bleeder of the type herein disclosed no left-hand threaded tubing is required, the bleeder being attached to standard right-hand threaded tubing of which there is always a plentiful supply at the well site.

40 I claim:

1. A tubing-bleeder detachably connecting two adjacent sections of right-hand screw-threaded well tubing and including a first collar screwed upon one of said tub-

ing sections, a second collar screwed upon 45 the adjacent tubing section and having a left-hand screw-threaded engagement in the first collar permitting a separation of the two sections by a right-hand rotation of one section relative to the other, and a barrel carried by the first collar and surrounding the second collar and adjacent tubing section and provided with a stop abutment with which the second collar engages to limit the separation of the two sections, the barrel having 50 perforations allowing the escape of liquid from the tubing when the sections are separated.

2. In a device of the class described, the combination with a well casing and a pump 60 tubing therein comprising a plurality of sections of right-hand screw-threaded tubing, means separably connecting two adjacent tubing sections and operable to bleed the tubing, said means comprising a first collar 65 screwed upon one of said sections, a second collar screwed upon the adjacent section and having a left-hand screw-threaded engagement in the first collar permitting a separation 70 of the two sections by a right-hand rotation of the one section relative to the other, a barrel carried by the first collar and surrounding the second collar and adjacent section and provided with a stop abutment with which the second collar engages to limit 75 the separation of the two sections, the barrel having perforations allowing the escape of liquid from the tubing when the sections are separated, and coacting means on the tubing and the casing below the bleeding means 80 to seal the space between the tubing and casing upon a lowering of the entire tubing.

Signed at Los Angeles, California, this 6th day of June, 1922.

FRED NELSON CRIPPEN.
